UNITED STATES PATENT OFFICE.

ARTHUR C. KOOTZ, OF MILWAUKEE, WISCONSIN, ASSIGNOR TO GEM HAMMOCK & FLY NET COMPANY, OF MILWAUKEE, WISCONSIN, A CORPORATION OF WISCONSIN.

WASH MOP.

Application filed July 12, 1926. Serial No. 121,881.

The invention relates to wash mops.

The general objects of the invention are to provide a wash or water mop which is of simple and economical construction and efficient in operation. While the mop embodying the invention may be used for various purposes it has been especially designed for use in washing motor-driven vehicles so that the device may be used as a hand water brush for washing the sides of the vehicle and as a mop water brush with a long handle for washing the top of such vehicles.

The invention further consists in the several features hereinafter set forth and more particularly defined by claims at the conclusion hereof.

In the drawings: Fig. 1 is a plan view of a wash mop embodying the invention, parts being broken away and parts being shown in section;

Fig. 2 is a vertical sectional view taken on the line 2—2 of Fig. 1 parts of the hose coupling being broken away to show one of 25 the branch outlets;

Fig. 3 is a detail sectional view taken on the line 3—3 of Fig. 1.

In general, the device comprises a hose coupling or fitting 4, a distributor pipe 30 and mop support 5 in the form of a loop, and the mop element 6.

The fitting 4 has a threaded opening 7 for connection with a male coupling attached to the hose and branch pipes or conduits 8 communicating with said opening and diverging from each other and disposed at an angle to the axis of the opening 7.

While the support 5 may be a rubber hose provided with spray openings on its under- 40 side, I prefer to use a flexible metal conduit composed of spirally wound metal strips 9 whose joints permit the flow of water through them. The metal conduit which I have found well adapted for this purpose is such as is used in the electrical art for housing and armor for electrical conductor wires, the joints between convolutions of this conduit being such that the water flowing into the fitting 4 will pass uniformly 45 out of the conduit along its length. The ends 10 of this conduit are firmly affixed to the branch conduits 8 by forcing them over these ends which have a series of toothed annular flanges 11 which permit the conduit 50 being forced on but which, due to the rear-

ward inclination thereof, prevent its being pulled off or working loose.

The mop element 6 consists of layers 12 of yarn or other suitable soft absorbent material said layers being secured together by spaced rows of stitching 13 on opposite sides of their central portions to form a channel or passage 14 through which the conduit or support 5 extends and to reinforce said element and at the same time prevent the free flow of water from the top and sides of the distributor conduit a strip of canvas 15 or other closely woven fabric is secured over the outer layer of mop material by the stitching 13. The mop material is placed on the distributor conduit as shown before the ends of said conduit are secured to the branch pipes of the fitting 4 and the ends of this mop material are then tightly bound together by a cord passing through openings 16 on the under side of said ends and through the canvas strip 15 so that ends of the mop can not work out toward the center of the loop of said distributor conduit.

With this construction the water coming through the conduit 6 passes down through the lower layer of the mop material and flows onto the article being washed and the mop strands become wet and act like a sponge to loosen the dirt and other foreign matter, the device being readily manipulated by holding it in the hand adjacent the fitting 4.

In order to use the wash mop in places which are not readily accessible such as the top of a vehicle, the fitting 4 is provided with an apertured pivot lug 17 and a pivot bolt 18 passes through the opening in this lug and through the spaced ears 19 of a handle coupling 20 which has socket portion 21 receiving the handle 22 and provided with spaced lugs 23 that are drawn together to clamp the handle in the socket by a screw bolt 24. The handle 22 may be readily removed from the socket when the device is used as a hand mop.

I desire it to be understood that this invention is not to be limited to any particular arrangement or construction of parts except in so far as such limitations are included in the claims.

What I claim as my invention is:

1. In a wash mop, the combination of a hose coupling provided with branch conduits, a helically coiled flexible metal distributor conduit in the form of a loop se-

105

110

cured at its ends to said branch conduits, and a mop element having parts surrounding said conduit and securing it thereto.

2. In a wash mop, the combination of a 5 hose coupling provided with branch conduits, a handle coupling pivotally secured to said hose coupling above its inlet, a looped distributor conduit secured at its ends to said branch conduits and a mop element 10 having parts surrounding said conduit and securing it thereto.

3. In a wash mop, the combination of a hose coupling provided with branch con-

duits, a looped distributor conduit secured at its ends to said branch conduits, and a 15 mop element having inner and outer layers of mop strands stitched together in spaced relation at their central portion to form a channel in which said distributor conduit is disposed, and a strip of fabric extending 20 over said outer layer adjacent the top and sides of said distributor conduit.

In testimony whereof, I affix my signature.

ARTHUR C. KOOTZ.
